J. KISH,
CLOTHESLINE HOLDER,
APPLICATION FILED JAN. 7, 1920.

1,354,109.

Patented Sept. 28, 1920.

INVENTOR.
Joseph Kish

BY
Harry Jacobson
ATTORNEY.

UNITED STATES PATENT OFFICE.

JOSEPH KISH, OF JOHNSTOWN, PENNSYLVANIA.

CLOTHESLINE-HOLDER.

1,354,109.

Specification of Letters Patent. Patented Sept. 28, 1920.

Application filed January 7, 1920. Serial No. 349,974.

To all whom it may concern:

Be it known that I, JOSEPH KISH, citizen of the United States, and resident of Johnstown, in the county of Cambria and

5 State of Pennsylvania have invented certain new and useful Improvements in Clothesline-Holders, of which the following is a specification.

This invention relates to clothes line 16 holders, and especially to that type in which the pulling force on the ends of the line may be adjusted to meet varying conditions.

The object of this invention is the provision of conveniently positioned means 15 easily manipulated by a person from the inside of a window, for tightly holding a clothes line, and for making the fastening of clothes on said line easy.

A further object of this invention is the 20 provision of means for changing the pull on the line for substantially eliminating the sag on said line under varying weather conditions.

For the accomplishment of the aforesaid 25 objects, I employ the devices shown in their preferred forms in the accompanying drawings, in which,

Figure 1 is a plan view of my device as it appears attached between two windows.

30 Fig. 2 is a front elevation of the same.

Fig. 3 is a vertical section of a detail of the clothes line shifting device on line 3—3 of Fig. 4.

35 Fig. 4 is a horizontal section on line 4—4 of Fig. 3.

In the practical embodiment of my invention, the conical clothes line pulley 1, preferably of wood or other suitable material which does not injure the clothes coming in contact therewith, is provided with 40 cleats 2 arranged in space relation along elements of the conical surface of said pulley. The upper end 3 of said pulley carries a multiplicity of handles 4 arranged radially 45 for turning said pulley about vertical stud bolt 5 which is pivotally supported by curved arm 6 from window frame 7 at joint 9 by means of angles 8. The lower end 16 of pulley 1 is flared to prevent a clothes line 50 passing around said pulley from working off the end thereof. A similar clothes line pulley 11 is arranged at the desired distance from pulley 1 and is swingably supported in the same manner as pulley 1, though the 55 handles 4 may be dispensed with on pulley 11. The clothes line 10 is passed around

pulleys 1 and 11, the rotation of said pulleys tending to cause said line to creep toward the widest part of said conical pulleys 1 and 11, whereby the line 10 is stretched taut. 60

To provide for cases where the sag in said clothes line cannot be entirely taken up by the rotation of pulleys 1 and 11, additional means are provided for that purpose, comprising turnbuckle 12 attached to arm 6 at 65 joint 13 and supported at its other end from window frame 7 by angle 14 at joint 15. It is obvious that if clothes line 10 is caused to sag too much or becomes too tight because of varying weather or other conditions, the 70 pull on said line may be quickly increased or diminished by means of turnbuckles 12. In hanging clothes on the line, the person who is doing the hanging may stand comfortably inside window 7, pulley 1 being 75 within easy reach. Clothes pins holding the clothes may be quickly attached to the line at the spaces between cleats 2, so that said pins cannot interfere with the manipulation of said pulleys and of line 10. 80

It is obvious that every portion of the line is available for hanging clothes thereon, whereby my device is economical on line space.

What I claim is:—

1. In a device of the character described, a conical pulley spaced means on the conical surface of said pulley for receiving pins therebetween, handles projecting radially from said pulley for rotating said pulley, 90 and a flared bottom end on said pulley for preventing a line passed around said pulley from leaving said pulley. 85

2. In a device of the character described, a conical pulley arranged with the smaller 95 end up, cleats having a flat outer surface, arranged in space relation to each other along elements of the conical surface of said pulley and adapted to have a clothes line passed around said cleats whereby said line 100 tends to creep to the larger end of said pulley to tighten the line on the rotation of said pulley, a cylindrical head on said pulley larger in diameter than the upper end of the conical part of the pulley, a series of 105 handles projecting radially from said head for rotating said pulley, and a flared bottom end on said pulley for preventing said line from leaving said pulley.

3. In a device of the character described, 110 a conical pulley, cleats having a flat outer surface arranged in space relation to each

other along elements of the conical surface of said pulley, handles projecting radially from said pulley for rotating said pulley, a flared bottom end on said pulley for preventing a line passed around said pulley from leaving said pulley, and adjustable means coöoperating with said pulley for

tightening and loosening said line and for supporting said pulley.

Signed at Johnstown, in the county of 10 Cambria and State of Pennsylvania, this 2nd day of January, A. D. 1920.

JOSEPH KISH.
